Primary Examiner — Karen E Eldridge Powers*Assistant Examiner* — Kimberly Barnes(74) Attorney, Agent, or Firm — Gurr & Brande, PLLC; Robert A. GurrCLAIM

The ornamental design for headwear with flapped bill, as shown and described.

DESCRIPTION

FIG. 1 is a perspective view of the headwear;

FIG. 2 is a top plan view of the headwear;

FIG. 3 is a front elevation view of the headwear; and,

FIG. 4 is a side elevation view of the headwear.

The broken lines showing the crown portion of a hat depicts environmental subject matter only and forms no part of the claimed design.
